United States Patent Office

Des. 184,759
Patented Mar. 31, 1959

184,759

TABLE

Walter P. Myers, Chicago, Ill.

Application November 7, 1957, Serial No. 48,376

Term of patent 14 years

(Cl. D33—14)

Fig. 1 is a perspective view of the table embodying the new design;

Fig. 2 is a side elevational view of the table shown in Figure 1;

Fig. 3 is a plan view of the table in Figure 2; and

Fig. 4 is a front elevational view of the table shown in Figure 3.

The dominant feature of the design being shown in solid lines.

I claim:

The ornamental design for a table, as shown and described.
